UNITED STATES PATENT OFFICE.

EDWARD L. ACKERMAN, OF DETROIT, MICHIGAN, ASSIGNOR TO JOS. N. SMITH & COMPANY, OF DETROIT, MICHIGAN, A CORPORATION OF MICHIGAN.

AUTOMOBILE-DOOR LATCH.

1,170,863.

Specification of Letters Patent.

Patented Feb. 8, 1916.

Application filed November 23, 1914. Serial No. 873,539.

To all whom it may concern:

Be it known that I, EDWARD L. ACKERMAN, a citizen of the United States, and a resident of Detroit, in the county of Wayne and State of Michigan, have invented a new and useful Automobile-Door Latch; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to automobile latches and it has for its object to provide a combined automobile latch which holds the door securely in closed position and operates to keep the door from rattling and to start the door when it is unlatched. The latch is located well below the top of the door while the striker plate extends inwardly with respect to the door and is located so as to engage with the catch of the latch and to receive the thrust of a buffer head.

The invention may be contained in many forms of constructions usable for different purposes, all of which come within the purview of my claims hereinafter appended. To show the practicability of my invention, I have selected one of such constructions as an example and shall describe it herein-after. The construction selected is illustrated in the accompanying drawings.

Figure 1 of the drawing illustrates the latch applied to an automobile body. Fig. 2 is a side view of the latch showing a part of the automobile body broken away. Fig. 3 is a perspective broken view of the latch. Fig. 4 is a vertical sectional view of parts of the latch.

1. Fig. 1, is the automobile body.

2 is the door having the usual hinges.

4 is the latch which is located at the edge

15 and well below the top of the door.

The parts of the latch are mounted between two plates 10 and 11 which are secured together by means of lugs 12 which extend into slots or holes formed in the right angular plate 11. The plates are riveted together by means of the pin 13. The rivet pin 13 also forms a pivot pin about which the right angular latch lever 14 may rotate a short angular distance. The latch

lever 14 is provided with an arm 15 which extends upward through the top of the door 2. Its upper end is provided with a handle 16 which extends over and within the plane of the inner surface of the door 2. The latch part 17 of the latch lever 14 extends at right angles to the arm 15. It is provided with a nose 18 which extends at right angles to the latch part 17 and inwardly within the plane of the inner surface of the door. It extends through a slot 19 located in the plate 11 of the lock. The upper edge of the latch part 17 is depressed at 20 which gives room for vertical swinging movements of the latch part 17 with respect to a coiled spring 21 which is secured at one end to a pin 22 having a slotted end which receives the inner end of the coiled spring. The outer end of the coiled spring has a curved lip 23 which presses against the outer end of the latch part 17 and operates to yieldingly hold the latch part 17 down. Just beneath and in close proximity to the nose 18 and the slot 19 through which the nose extends there is located a buffer comprising a thimble 25 which extends through a hole 26 formed in the plate 11. A spring 27 is placed in the thimble 25 and is compressed by the plate 10 when the plate 10 is placed in position relative to the plate 11. The buffer 25 is provided with a flange 28 which limits the movements of the spring and retains the buffer in the plate 11. The flange 28, the spring 27, and the plates 10 and 11, coöperate to hold the buffer in position in the plate 11.

The striker plate is secured to the body of the automobile by means of screw bolts which pass through the holes 30. The plate 29 itself extends inward with respect to the door and is provided with a slot 31 which is adapted to receive the nose 18 of the latch. The lower edge 32 of the slot 31 is beveled and coöperates with the nose 18 to lift the latch when the door is closed. The striker plate extends over the edge of the lock and so as to receive the thrust of the buffer thimble 25. The buffer thimble 25 strikes the striker plate in proximity to and just below the slot 31. The buffer coöperates with the latch in securely holding the door closed and at the same time yieldingly forcing the door open when the latch is released from the striker plate. They

also coöperate to prevent any rattling of the door and of the parts of the lock when the door is closed.

It will thus be seen a very efficient, yet simple lock is provided and one wherein the parts may be easily assembled. The construction selected and described, may be greatly varied in the arrangement and manufacture of its parts and in the substitution of elements having equivalent functions and such modifications may be used for many varied purposes and still contain the invention.

Having thus described my invention, what I claim as new, and desire to secure by Letters Patent, is,—

1. In an automobile door latch, the combination of a right angular latch lever located within the door and having an upwardly extending arm extending without and above the upper edge of the door, plates located on each side of the latch lever for pivotally supporting the latch lever, the latch lever having an engaging nose extending upwardly and through one of the plates and at right angles to the plane of the lever, the latch lever having a depressed portion and a coiled spring located above the latch lever and between the plates and within the area of the depressed portion of the latch

lever, an angular striker plate, one side of which overlaps the lever supporting plates and having a recess for engaging the nose of the latch lever.

2. In an automobile door latch, the combination of a right angular latch lever, the latch lever having an upwardly extending arm for operating the lever, a pair of plates for pivotally supporting the lever, a coiled spring for operating the latch lever, the latch lever having an engaging nose extending upwardly and at right angles to the plane of the lever, one of the plates having an opening through which the engaging nose is located, a buffer thimble located below and in proximity to the nose of the latch lever and extending through one of the plates and in the direction in which the engaging nose extends, a striker plate having a recess for receiving and engaging the engaging nose of the latch lever, and receiving the thrust of the buffer thimble.

In testimony whereof, I have hereunto signed my name to this specification in the presence of two subscribing witnesses.

EDWARD L. ACKERMAN.
